UNITED STATES PATENT OFFICE.

LUDOVIC ESTIS HUNT, OF SPRINGFIELD, MISSOURI.

LATHE-TOOL.

1,319,585.

Specification of Letters Patent. Patented Oct. 21, 1919.

Application filed November 25, 1918. Serial No. 264,078.

To all whom it may concern:

Be it known that I, LUDOVIC E. HUNT, a citizen of the United States, and a resident of Springfield, in the county of Greene and State of Missouri, have invented certain new and useful Improvements in Lathe-Tools, of which the following is a specification.

My invention is an improvement in lathe tools, and has for its object to provide a tool of the character specified to replace the usual tailstock center in the tailstock of a turning lathe, for permitting the desired degree of taper to be obtained by the adjustment of the tool.

In the drawings:

Figure 1 is a plan view of the device in the position in which it is used;

Fig. 2 is a transverse section;

Fig. 3 is a side elevation.

In the present embodiment of the invention a holder is provided in the form of a cross head, consisting of a body 1 and a central stem 2, the said stem being a standard lathe center shank. The body 1 of the holder has its opposite side walls undercut, as shown, to form an undercut rib, and a slide 3 of substantially U-shape in cross section is mounted to slide upon the rib.

The holder has laterally extending flanges 4 at its opposite sides, and the edges of the side walls of the slide abut these flanges. The slide is held in adjusted position on the holder by means of clamp screws 5. Each clamp screw is journaled in one side wall of the slide and has threaded engagement with the other side wall, so that by means of the set screws the side walls may be tightened upon the body of the slide. The slide 3 has a central centering stem 6 which is adapted to engage and center the work, and it will be obvious that when the slide is moved longitudinally of the holder the centering stem will also be moved.

An internally threaded opening 7 is provided in one end of the holder body, and a screw 8 having a knurled head 9 is engaged with the opening. A dial plate 10 is secured to that end of the slide adjacent

to the opening 7, and the screw 8 has a plain portion which engages a central opening in the dial plate. At one side edge the dial plate has an inwardly offset inwardly extending rib 11 connected to the body of the dial by a web, and this rib engages similarly shaped notches in the edges of the side walls of the slide. Screws 12 connect the other edge of the dial plate with the slide. The dial has an annularly graduated scale 13, and the knurled head 9 of the screw 8 has an indicator 14 coöperating with the scale, to indicate the position of the screw with respect to the dial and with respect to the body 1 of the holder.

A coil spring 15 encircles the screw, between the dial and the adjacent end of the body 1 of the holder, the said spring acting normally to press the slide and the dial away from the holder, that is, the screw moves the holder and the dial in one direction and the spring moves them in the opposite direction.

In practice, when it is desired to cut a taper, the screws 5 are loosened and by means of the screw 8 the slide is adjusted to the proper relative position with respect to the body 1 of the holder. The amount of off centering is indicated on the dial by the indicator. When the proper degree of off center is attained, the parts are clamped together by means of the set screws 5. It will be noticed that one of these set screws is arranged at each end of the slide.

I claim:

A device of the character specified comprising a holder having a standard center shank, and having at its opposite side a rib provided with undercut side walls, a slide provided with a groove for receiving the rib and carrying a centering stem, a set screw having threaded engagement with the holder, said screw having a head extending beyond the slide at one end, a plate detachably connected with the slide at the said end and having an opening through which the stem passes, and a spring between the plate and the adjacent end of the holder and normally acting to move the slide toward the head of the screw.

LUDOVIC ESTIS HUNT.
